UNITED STATES PATENT OFFICE.

WILLIAM A. RINGLER, OF NEW YORK, N. Y.

SAFETY FILING SYSTEM

1,332,954.

Specification of Letters Patent.

Patented Mar. 9, 1920.

Application filed November 19, 1918. Serial No. 263,152.

To all whom it may concern:

Be it known that I, WILLIAM A. RINGLER, a citizen of the United States, residing in the city of New York, borough of Manhattan, and State of New York, have invented certain new and useful Improvements in Safety Filing Systems, of which the following is a full, clear, and exact description.

10 My invention relates to filing systems in which the component elements are arranged in such a manner that the position of anyone of them may be quickly ascertained. In order that such systems may be
15 of practical utility, means for guarding against the misfiling of an element must be provided. As some of these systems sometimes have to provide for as many as forty thousand active accounts, if one of the account elements is inadvertently misfiled, it
20 is almost impossible to locate it. In order to positively obviate the misfiling of such elements and to render such misfiling, when it has occurred instantly apparent, is one of the principal objects of my invention.

25 While I am aware that numerous filing or so-called safety card index systems are known, none of them provides positive means for guarding against the misfiling of an element, and this is principally due to
30 the fact that the notches of adjacent groups are offset or displaced. Because of this offsetting of the notches of the adjacent groups it frequently happens that one of the cards is filed in such position as to be
35 covered by the preceding card and hence not discoverable. In order to obviate this difficulty I have so located the notches of the adjacent groups that a continuous channel or groove is provided, the entire length
40 of which is readily viewable and the incorrect filing of an element quickly ascertainable.

In addition to the checks, above indicated, which guard against the misfiling of an element in an incorrect position in a given drawer, I have also provided means for guarding against the misfiling of an element in the wrong drawer. This feature is of considerable importance since the elements of most filing systems are, for the sake of convenience, distributed through more than one drawer or receptacle.

more than one drawer or receptacle.

While I have exemplified a system for filing cards, it is to be understood that my invention is equally applicable to letter fil-

ing systems, and similar systems, by providing the files or folders which contain the correspondence with indicating means similar to those provided for the cards of the system herein disclosed.

The drawings accompanying this specification and forming part thereof exemplify one form and embodiment of my invention, in which—

Figure 1 shows a perspective view of 65 some of the assembled elements comprising my system;

Fig. 2 shows a front elevation of Fig. 1; Fig. 3 shows a front elevation of one of the ledger cards; and

Fig. 4 shows a front elevation of some of the elements of my system with some of the elements in modified position to facilitate posting.

Referring to the drawings, it will be seen 75 from an examination of Fig. 1 that the elements comprising my system are divided by appropriate cuts or notches into groups and sub-groups. The largest group which I will designate hereafter for purpose of convenience as a section is indicated by A. This section is composed of as many elements as is desired and which will hereinafter be more fully explained. All of the elements of each section have one upper corner cut or biased 80 and when in registry provide a smooth beveled edge for all of the elements comprising each section as shown. The beveled edges of adjacent sections are oppositely disposed to guard against misfiling of an element in the wrong section. Each section 85 A is divided into a plurality of sub-groups B, which I will term major groups, each of 90

13, which I will term major groups, each of which groups is provided with openings or notches 13, the notches of each major group 95 B registering with each other while the notches of the adjacent groups overlap, so as to provide a substantially continuous and readily viewable channel, which renders mis-filing of an element in the wrong major 100 group readily apparent. Each major group B is further divided into smaller sub-groups C, (i. e., containing a lesser number of elements) and having openings or notches 14 similar to those provided for the major 105 groups B. I will, for the sake of convenience, designate the group C as a minor group. Each of the major groups B and the minor groups C has associated therewith a coöperating index card 10 located in front 110

of such group. Each index card 10 (and it will be understood that a plurality of such cards is employed) is provided with an index tab 11 on which may be indicated divisions and sub-divisions of the alphabet and a number corresponding to a number placed on the ledger cards as will be described. Each card 10 has a beveled corner 12, for controlling the filing of elements in section 10 A, notch 13 for controlling the filing of elements in section B and notch 14 for controlling the filing of elements in the sections C. The ledger card 15 shown in Fig. 3 is provided with a beveled corner 16 and notches 17 and 18 corresponding to and coöperating respectively with the beveled corner 12 and notches 13 and 14 of the index card 10. It will be understood that any convenient number of ledger cards are associated with each 20 index card, and the section A and groups B and C may comprise any convenient number of elements. The indicating notch 17 or 18 is provided for each of the ledger cards and the index card forming a major group B, 25 the notches in the elements of each group B registering and forming a smooth groove, as shown. The grooves formed in the elements comprising adjacent major groups are so positioned that the grooves partly overlap so as to form a continuous channel of 30 all the grooves comprising a section A.

The elements comprising each of the secondary sub-groups C into which the previously mentioned major group B is divided, 35 have safety notches 18 coöperating with safety notches 14 of index card 10, and so arranged that the notches comprising each adjacent group C are eccentric to each other so as to provide a continuous channel for the 40 grooves of the groups C which form a major group B. Suitable scales as D and E may be provided for conveniently indicating the proper position for the notches.

Each of the cards adapted to be placed in 45 a given cabinet or drawer is provided with one or more guide openings 19 in the bottom thereof, all of which register with and are adapted to engage one or more guide rods 20, which extend longitudinally of the assembled cards. The proper position of the notches 19 may be indicated by suitable scales as F and G on the lower edge of each. In the drawings, the scales F and G are shown as indicating seven positions, the 50 rod on the right being shown in the illustrated example in the first position while the rod on the left is shown in the third position and hence a card having lower notches corresponding to these positions can 55 only be filed in the drawer having the rods in a corresponding position. Manifestly various permutations and combinations may be made by suitably locating the rods of different drawers in different positions and the 60 number of rods may be increased whereby 65

the number of possible combinations may also be increased. Each ledger card is further provided with a secondary notch 21 at its lower edge in addition to the notches 19 above described. This secondary notch 21 provides a convenient means for retaining the ledger cards in such position that one end may project beyond the assembled cards for posting purposes, as shown in Fig. 4. Thus if an entry has been made on one of 75 the ledger cards, the card may be moved to such a position that the notch 21 engages one of the rods 20, thereby causing that particular card to project beyond the edges of the remaining cards. As it is customary 80 each evening to post the entries made on the individual ledger cards, these ledger cards may thus be quickly picked out. The notch 21 of the ledger card, illustrated in Fig. 3, is designed to be used in cases where but one 85 guide rod 20 is used, although by providing additional notches as 21, it can be adapted for use with more than one rod.

Manifestly, the provision of overlapping notches for the adjacent groups B and C 90 provides a continuous channel, as shown in Fig. 1, thus obviating the possibility of incorrectly filing the elements by preventing a misfiled ledger card from becoming totally concealed by one of the other cards. 95

Each index card 10 has preferably indicated thereon a letter corresponding to a sub-division of the alphabet, and a number (in the illustrated example) Ta and 3100 respectively. The number 3100 indicates 100 drawer 31 because the left hand notch 19 is cut from the third position and the right hand notch 19 is cut from the first position while notches 13 and 14 are cut out at the o, o positions as indicated by scales D and 105 E. All the ledger cards of the first minor division have their notches located in corresponding positions, and each ledger card has a number corresponding to these positions inscribed on its face. That is 3100 in the 110 illustrated example. The cards of the succeeding minor section would be numbered 3101, 3102, etc., while the cards of the succeeding major group would be numbered 3110, 3111, 3112, etc. 115

I claim:

1. A filing system comprising a plurality of grouped elements having notches so disposed relatively to each other as to overlap. 120
2. A filing system comprising a plurality of elements divided into groups, each group having notches, the notches of adjacent groups being so disposed relatively to each other as to overlap. 125
3. A filing system comprising a plurality of elements divided into groups, each group having notches, the notches of each group registering with each other and the notches of adjacent groups being so disposed relatively to each other as to overlap. 130

4. A safety index system comprising a plurality of elements divided into sections, major and minor groups, the elements comprising a section having beveled edges, the beveled edges of each section registering with each other, the elements comprising a major group having notches which register with each other and the elements comprising a minor group having notches which register with each other, the notches of the successive major and minor groups being so disposed relatively to each other that a series of continuous grooves for each series of groups is formed.
5. An element for filing systems having a beveled corner and safety notches cut from one edge.
6. An element for filing systems having safety indicating notches cut from one edge and guide notches cut from the opposite edge.
7. An element for filing systems having a beveled corner, safety indicating notches cut from one edge and guide notches cut from the opposite edge.
8. A filing system comprising a plurality of index cards and a plurality of ledger cards, associated with each index card, forming a group, the index card and the associated ledger cards having notches which register with each other and a number corresponding to the position of the notches and indicating the position of the card in the system.
9. A filing system comprising a plurality of index cards and plurality of ledger cards associated with each index card, the index cards and ledger cards having notches and a number, the number being determined by the position of the notches and the position of the notches determined by the relative position of the cards in the system.

In witness whereof I subscribe my signature.

WILLIAM A. RINGLER.
